SANDAL OR SIMILAR ARTICLE

Walter Braun, Los Angeles, Calif., assignor to Cobblers Incorporated, Los Angeles, Calif., a corporation of California

Application November 23, 1951, Serial No. 17,510

Term of patent 7 years

(Cl. D7—7)

To all whom it may concern:

Be it known that I, Walter Braun, a citizen of the United States, residing at Los Angeles, in the county of Los Angeles, State of California, have invented a new, original, and ornamental Design for a Sandal or Similar Article, of which the following is a specification, reference being had to the accompanying drawing forming a part thereof.

The dominant features of the design are shown in full lines, the design being characterized by the particular heel strip which extends from the top edge of the outer sole, over the wedge element and over the insole for some distance as shown.

I claim:

The ornamental design for a sandal or similar article, as shown and described.

WALTER BRAUN.
